(57) **CLAIM**

The ornamental design for a phone case, as shown and described.

DESCRIPTION

FIG. 1 is a top front right perspective view of a phone case, showing my new design;

FIG. 2 is a bottom front right perspective view thereof;

FIG. 3 is a top rear left perspective view thereof;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof; and,

FIG. 9 is a bottom plan view thereof.

The broken lines shown in the drawings depict portions of the phone case that form no part of the claimed design.

1 Claim, 5 Drawing Sheets
